UNITED STATES PATENT OFFICE

LOUIS D. SUMMERS, OF DECATUR, ILLINOIS, ASSIGNOR, BY MESNE ASSIGNMENTS, TO LEADER IRON WORKS, INC., OF DECATUR, ILLINOIS, A CORPORATION OF DELAWARE

BOILER AND WATER HEATER

Application filed September 22, 1927. Serial No. 221,368.

This invention relates to boilers and water heaters adapted to be used with fuels such as oil and gas for heating water or generating steam for heating systems; an object being in this case to provide a boiler and water heater that will be economical to manufacture, practical and convenient to install and one that will develop a high percentage of efficiency in heat transfer.

10 A further object of my invention is to provide in a boiler and water heater using oil or gas fuels an arrangement by which I accomplish the maximum of heat transfer from the products of combustion as long as the heated gases are permitted to remain in the gas tubes before such gases are discharged from the heating plant in their coolest state.

20 A further object of my invention is to provide a boiler and water heater for using gas and oil fuels having in integral combination therewith a heat economizer compartment adapted to economically and effectively utilize the principle of counterflow whereby the slowly heating water rises to the upper area of the boiler section while the hot gases slowly settle to a lower level through the gas tubes in approaching the flue outlet therefor.

25 With these and other objects in view this invention concerns improvements in boiler construction, the details of which will be hereinafter explained in the following paragraph and illustrated in the drawings forming a part of this specification, in which drawings like numerals indicate like parts in the several figures.

30 Referring to the figures:

Fig. 1 is a top view of my boiler and water heater.

35 Fig. 2 is a side elevation thereof, disclosing in a cut-away certain interior details of construction of my boiler and water heater.

40 Fig. 3 is a vertical half-section of my boiler and water heater taken from front to back.

45 Fig. 4 is a horizontal cross section taken A—A of Fig. 2.

Fig. 5 is a horizontal cross section taken B—B of Fig. 2.

50 Fig. 6 is a horizontal cross section taken C—C of Fig. 2.

When burning oil or gas as fuels especially

it is an important item to have as much of water chamber surfaces as possible come in direct contact with the hot gases from the combustion chamber and in this connection I am providing an arrangement of structure in my boiler and water heater that will permit the hot gases from the combustion chamber to pass up through a plurality of relatively small tubes and then through an upper gas chamber from where they settle through a plurality of relatively larger gas tubes before passing out to the house flue through a lower gas chamber connected with the flue.

In burning fuels it is necessary to maintain a temperature varying from 900 to 1600 degrees Fahrenheit in order to produce combustion and when the flame while in the process of combustion touches a surface having a temperature less than approximately 900 degrees it tends to break down the carbon forming what is commonly known as soot which covers the surface with which it comes in contact tending to form a coating of the same over such surfaces that would somewhat insulate the surface from the heat from the products of combustion making it harder to heat the surface and thus accomplish a heat transfer to and through the surfaces with which the products of combustion are adapted to come into contact.

In order therefore to provide a boiler and water heater of suitable efficiency, I provide an arrangement of details of structure whereby the combustion chamber of the heating plant is uprightly and eccentrically disposed therein.

The combustion chamber is encompassed by a water compartment and provided with a group of upright gas tubes relatively small in size extending through the water chamber so that as the hot gases pass upward from the fire box through these tubes which are surrounded by water communicating with the central water chamber they come in contact with a greater surface area for heating the water, especially since the construction of my boiler and water heater provides for the hot gases to settle by heat stratification down through a plurality of relatively larger gas tubes partially surrounding the combustion

chamber and also extending through the central water chamber in an upright position.

Referring in detail to the several parts of my boiler and water heater and the relation of each to the entire structure I provide a combustion chamber —1— for burning gas and oil and the like in a burner —2—.

Above combustion chamber —1— which is encased by casing —3— I provide a plurality of upright gas tubes —4— to accommodate the hot gases as they ascend toward upper gas chamber —5— from which the hot gases descend to lower gas chamber —6— through a plurality of gas tubes —7— before they pass out to the house flue through upright flue —8—.

Central water chamber —9— surrounds combustion chamber —1— while fire tubes —4— and —7— are so mounted as to extend entirely through central water chamber —9—.

Tubes —4— are secured into operating position by upper plate —10— and lower plate —11— while tubes —7— are secured to upper plate —10— and lower plate —12—.

Tubes —4— are surrounded by a portion of central water chamber —9— positioned above the combustion chamber and indicated by numeral —13—.

Water chamber —9— however, communicates with chamber —13— at the lower position through aperture —14— and in the upper area through aperture —15—.

Water chamber —9— connects with relatively thin water chamber —16— above the upper gas chamber —5— through tubes —17—, —18—, and —19—.

Relatively thin water chamber —16— is provided above upper gas chamber —5— in order to give an especially hot application of the hot gases to the water in chamber —16— just before it leaves the boiler through outlet —20— to go out over the heating system, which in this case could be either steam or hot water.

Numeral —21— indicates the control pipe for the supply of oil or gas while numeral —22— indicates an aperture through which the operator may observe the flame as the oil or gas burns.

Casing —23— surrounds the combustion chamber, central water chamber, upper water chamber —16—, upper gas chamber —5— and lower gas chamber —6—.

Water gauge —24— is provided for the information and safety of the operator while steam gauge —25— is provided for safety.

A cold water intake is provided at the lower connection indicated by spud —26— positioned in the rear of casing —23— nearer the lower area of the water chamber —9—.

The hot products of combustion may be passed directly to the house flue —8— from combustion chamber —1— through short circuit pipe —28— into flue pipe —8— by thermostatic influence on automatic by-

pass damper —27— including a shutter —29— when it is desired to have the gases pass down into lower gas chamber —26— through gas tubes —7— and out flue —8—.

Numeral —30— indicates a floor plate on which the heating plant is adapted to normally rest.

This boiler is so designed as to recognize the principle of counterflow and stratification in heat transfer from the products of combustion over to water where it is desired to secure from a heating plant the highest possible efficiency.

All cold water return is brought in to the lowest part of the economizer section through spud —26— thereby bringing the coldest water in contact with the coldest gases before the gases leave the heating plant through the lower gas chamber of the house flue; by which method I secure the highest over-all efficiency in the heating plant.

The economizer section of the boiler and the central water section over the combustion chamber are cross connected through ports —14— and —15— respectively at the lower and upper levels and by this means the water is given a free circulation through the water compartment enabling the heating water to freely move to the point where it will absorb the most heat in the shortest time due to the physical laws governing the gravity movement of heating water. The boiler would then maintain what may be termed a thermostatic balance; that is, the tendency for the coldest water to remain on the bottom and the hottest water to be delivered to the respective water units of the boiler in proportion to the individual units ability to heat the same.

Hence to explain in detail: The water circulation in water chamber —9— where cold water enters this water chamber through cold water return pipe —26— where as it enters the water chamber —9— it receives an application of comparatively low temperature heat conducted from the hot products of combustion at their lowest temperature level before leaving the heating plant through pipe —8—. At this level the water rises as it becomes heated and by displacement is slowly moved on up by a new supply of incoming cold water and it may pass up and through aperture —14— where the heat transfer may be accelerated by the heat coming up through tubes —4— from the combustion chamber —1—.

Upper plate —10— provides a common covering for upright water chamber —13— and water chamber —9— which are communicatively connected through aperture —14— at the bottom of chamber —13— and aperture —15— at the top thereof. These two apertures are communicating openings in an upright cylindrical jacket —31— en-

compassing combustion chamber —1— as well as water chamber —13—.

To those skilled in the heating art it will be observed in the study of my invention that certain details of construction may be varied and would be permissible within the spirit and scope of my invention, but the preferred design and method of operation has been disclosed in the paragraphs above and illustrated in the drawings connected herewith.

Having thus described the merits and character of my invention and the preferred details of structure thereof, I claim:

In a fire tube boiler, an outer shell, a combustion chamber in the lower portion of said shell, a horizontal tube sheet above said combustion chamber; a set of relatively small upright fire tubes connected into said tube sheet and extending through a water chamber to an upper tube sheet and affording communication between said combustion chamber and an upper gas chamber formed above said upper tube sheet, a second set of relatively large fire tubes having a combined cross sectional area in excess of that of said relatively small fire tubes and extending from said upper chamber to a third tube sheet located below the level of the first mentioned tube sheet and surrounding the said combustion chamber, a smoke box below said lowermost tube sheet, an inner upright shell surrounding said set of relatively small fire tubes and said combustion chamber and having upper and lower water passages therethrough to afford communication between the water space inclosed by said shell and the water space surrounding said shell, said upper gas chamber being slightly spaced from the top of the boiler to provide a relatively thin steam space, a plurality of steam conducting tubes extending from the upper tube sheet to said steam space and communicating with said water chamber, a normally closed outlet from said upper gas chamber and an outlet for said lower smoke chamber communicating with said upper gas outlet and a gas discharge flue.

In witness whereof, I hereunto set my hand this 23d day of August, 1927.

LOUIS D. SUMMERS.
